UNITED STATES PATENT OFFICE.

WALTER H. BOWES, OF GREENWICH, CONNECTICUT.

ADJUSTABLE FEED AND DELIVERY PLATES AND ARTICLE-TRACK.

1,367,794.

Specification of Letters Patent.

Patented Feb. 8, 1921.

Application filed December 10, 1918, Serial No. 266,111. Renewed April 29, 1920. Serial No. 377,690.

To all whom it may concern:

Be it known that I, WALTER H. BOWES, a subject of the King of Great Britain, residing at Greenwich, in the county of Fairfield 5 and State of Connecticut, have invented certain new and useful Improvements in Adjustable Feed and Delivery Plates and Article-Track; and I hereby declare that the following is a full, clear, and exact description 10 thereof, reference being had to the accompanying drawings, which form part of this specification.

This invention is a novel improvement particularly designed for use in connection 15 with so-called stamp-canceling and postmarking machines, envelop sealing machines, and other machines designed to operate upon a number of articles, such as letters, checks, packages or other objects—that 20 are passed successively by or through the printing, sealing, stamping or other mechanism or mechanisms operating thereupon.

The principal object of the invention is to provide novel means whereby the track or 25 support along which the letters or other objects travel in passing to the operating means, or to and from such means, can be readily adjusted so that the said operating means can be caused to operate thereon at 30 the desired point, either higher or lower thereon, as desired. For instance, as applied to stamp canceling and postmarking machines, the track can be adjusted so that the printer will imprint the letters at any 35 desired point, which is a great advantage in postmarking machines, as it is sometimes desirable to print on the upper parts of the letters or articles at one time, at another time on the central part thereof, and at still 40 another time to print thereon near the lower edges thereof.

I will explain the invention as used in connection with a postmarking and stamp canceling machine; and applied thereto the invention enables such a machine to be readily 45 adjusted to make the impressions on the letters in any desired position without having to shift the position of the die or printing roller, inker, feeding mechanism, etc., and 50 the invention in brief provides an adjustable supporting means or track for guiding and supporting the letters or packages and directing them to and through the separating, forwarding, printing and delivering devices; and in the preferred form of the invention,—as applied to postmarking ma-

chines,—the feed table, the letter track and delivery table are practically unitary and are vertically adjustable as a unit relative to the sorting, separating, forwarding, 60 printing and delivering devices, and they can be readily adjusted as a unit to cause the letters or articles to be presented to said devices in such position as will insure their being marked at the desired position relative 65 to the height thereof.

This invention provides a very simple means for enabling different sizes of letters or packages to be properly marked in such machines; whereas, in existing machines of 70 this kind, it has been heretofore necessary to lengthen the shafts and adjust the printing member and ink roller to insure that the impressions will be made upon the letters in the desired positions. 75

The invention may be used in connection with means for printing, marking or otherwise operating upon letters or small packages, postal cards, envelops, checks and other objects, and I will hereafter for convenience 80 merely refer to these by the general term “article” intending thereby to include any article or thing which could be operated upon by machines to which the invention is applied. 85

The invention is illustrated as applied to a so-called “Universal” machine for canceling and postmarking mail, but as above stated the invention is applicable to various other types and kind of machines, and only 90 so much of the “Universal” machine as is necessary to impart a clear understanding of the invention is illustrated; and when understood it may be readily applied to various other types of machines by those skilled 95 in the art.

The accompanying drawings conventionally illustrate a stamp canceling and postmarking machine with one embodiment of my invention applied thereto, and I will explain the invention in connection with the 100 said drawings and refer to the claims for summaries of the invention and the novel features and combinations of parts for which protection is desired. 105

In the drawings:

Figure 1 is a conventional top plan view of a stamp canceling and postmarking machine with my invention applied thereto.

Fig. 2 is a side elevation of Fig. 1. 110

Fig. 3 is a vertical section on the line 3—3, Fig. 1.

Fig. 4 is a detail section on the line 4—4, Fig. 1.

In the drawings 1 designates the table, or top part, of the machine, which may be mounted on any suitable support; and from this table raise various shafts 2, 3, 4, 5, 6, and 7 upon which are respectively mounted the feed roller 2^a, the separating roller 3^a, the forwarding rollers 4^a, impression roller 5^a, printer 6^a and stacker wheel 7^a, which parts may be constructed and arranged to operate as in the "Universal" machine above referred to, and do not require any detailed explanation herein.

15 The feed table or plate A upon which the articles to be operated are stacked is shown as provided with a rear guard or fence D as usual adjacent the feed wheel 2^a and with a side guard or fence E as usual adjacent the 20 separator wheel 3^a. The fences D and E may be of any suitable construction as commonly used in such machines.

Said feed plate A underlies the rollers 2^a, 3^a as well as the main actuating wheel 8^a in 25 the construction shown; but instead of the plate A being mounted directly upon the table 1 it is fastened to an adjustable support or spider H, which is provided with a shank I that depends through an opening in 30 the table 1 and through a socket member J attached to said table, and said shank may be adjustably fastened in the socket by a set screw K, so as to support the feed plate at any desired height relative to the table 1.

35 The delivery table or plate B underlies the stacker wheel 7^a and carries the usual fence or guard F and stacker wheel guard G, and the usual devices for receiving the articles after they have been printed. This 40 delivery plate B instead of being attached directly to the table 1 is mounted upon a support or spider H' provided with a shank I' that extends through an opening in the table 1 and through a socket member J' attached to the table 1, and is adjustably secured to the member J' by a screw K'.

Intermediate and formed with or connected with the plates A and B and fastened thereto so as to form a unitary structure therewith is a plate C forming a letter track, which plate as shown lies below the wheel 8^a, rollers 4^a and 5^a and printer 6^a. This track plate 6 if sufficiently wide is perforated for the passage of the shafts carrying said rollers and printer. As shown the ends of track plate C are supported on flanges a, b on the edges of plates A and B respectively and secured thereto by set screw c.

The plates A, B, C and the spiders H, H' 60 form a practical unit; and this unit may be adjusted vertically, relatively to the underlying top 1 and the overlying parts 2^a, 3^a, 4^a, 5^a, 6^a, 7^a and 8^a without disturbing any of said parts or their operating devices; by 65 first loosening bolts K, K' then adjusting

the parts A, B, C and then resetting the bolts K, K' to hold the said parts A, B, C, in adjusted position.

By adjusting plates A, B, C vertically the point at which the impression or other operation on the articles will be made by the printer as the articles pass from the feed to the delivery in the machine can be varied; and the articles can be presented at any desired level or height relative to the printer or operating mechanism. Such adjustment can be made very quickly, and does not require the removal or manipulation or adjustment of any of the shafts or rollers, nor the changing of position of the printer 6^a, 80 impression roller 5^a, and rollers 4^a, etc., as the studs and shafts carrying the said operative parts of the mechanism pass freely through openings or slots made in the parts A, B, and C at the required points. 85

As stated the parts A, B and C practically form a unitary structure preferably extending throughout the entire length of the article travel in the machine, and such unitary structure can be raised or lowered 90 bodily by releasing the screws K, K' and secured when adjusted by tightening such screws. This renders it possible to quickly adjust the structure so that the articles will be presented to have the impressions or operations made at the desired position thereon as they pass through the machine, as above pointed out.

Claims:

1. In combination means for operating 100 upon articles, an article track upon which the articles are supported and move longitudinally thereof while being operated upon, and means for vertically adjusting said track.

2. In combination means for operating upon articles, an article track upon which the articles are supported and move longitudinally thereof while being operated upon, and means for adjusting said track relatively to said operating means. 110

3. In combination means for operating upon articles, article feeding means; an article track, and means for vertically adjusting said track and feeding means independently of and relatively to the operating means. 115

4. In combination means for operating upon an article, means for feeding and delivering the articles; an article track; and means for vertically adjusting said track and feeding and delivering means independently of and relatively to the operating means. 120

5. In combination means for operating 125 upon an article; a feed plate, an intermediate article track adapted to support the article being operated upon; and means for adjusting said feed plate and track relatively to the operating means. 130

6. In combination means for operating upon an article; a feed plate, a delivery plate, an intermediate article track adapted to support the article being operated upon; 5 and means for adjusting said feed plate, delivery plate, and track relatively to the operating means.

7. In a machine for postmarking and canceling stamps and the like, a printer and 10 means for operating said printer; an article track extending past the printer and upon which the articles are supported and move longitudinally thereof while being operated upon by the printer, and means for adjusting said track independently of and 15 relatively to the printer.

8. In a machine for postmarking and canceling stamps and the like having feeding means; a printer and means for operating 20 said printer; an article track, and means for vertically adjusting said track relatively to the feeding means and printer.

9. In a machine for postmarking and canceling stamps and the like having feeding 25 and delivery means, a printer and means for operating said printer; an article track, and means for vertically adjusting said track independently of and relatively to the feeding and delivery means and printer.

30 10. In a machine for postmarking and canceling stamps and the like having means for operating upon an article; a feed plate, a delivery plate, an intermediate article track connected with said plates and adapt- 35 ed to support the article being operated upon; and means for adjusting said feed plate, delivery plate and track relatively to the operating means.

11. In a machine for postmarking and 40 canceling stamps and the like, a feed plate; a delivery plate, a printer and means for operating said printer; with an article track between the feed and delivery plates, and means for vertically adjusting said feed 45 plate, delivery plate and track independently of and relatively to the printer.

12. In a machine for postmarking and canceling stamps and the like having feeding means, and delivery means; a printer 50 and means for operating the printer; with a feed plate, a delivery plate and an intermediate article track connected with said plates and adapted to support the article being operated upon, and means for adjust- 55 ing said feed plate, delivery plate and track independently of and relatively to the printer.

13. In a machine for postmarking and canceling stamps and the like having means 60 for operating upon an article; a feed plate, an article track connected with said plate and upon which the articles are supported and move longitudinally thereof while being operated upon; and means for adjusting

said feed plate and track as a unit relatively to the operating means. 65

14. In a machine for postmarking and canceling stamps and the like having means for operating upon an article; a feed plate, a delivery plate and an intermediate article 70 track intermediate and connected with said plates and adapted to support the article being operated upon, and means for simultaneously adjusting said feed plate, delivery plate and track as a unit independently of 75 said operating means.

15. In a machine for postmarking and canceling stamps and the like having feeding and delivery means, and means for operating upon an article; with a feed plate, a delivery plate and an intermediate article 80 track intermediate and connected with said plates and adapted to support the article being operated upon, and means for simultaneously adjusting said feed plate, delivery 85 plate and track as a unit independently of said operating means.

16. In combination a table and means mounted thereon for operating upon articles; with a feed plate; an article track 90 connected with said plate, said track being adapted to support the articles while being operated upon and a support for said plate adjustably connected with said table whereby said plate and track may be adjusted relatively to and independently of the operating 95 means.

17. In combination a table, article feeding means, delivery means, and means for operating upon articles mounted thereon; 100 with a feed plate, and an article track connected with said plate, said track being adapted to support the articles while being operated upon, supports for said plate adjustably connected with said table top 105 whereby said plate and track may be adjusted relatively to and independently of the operating means.

18. In combination, a table, article feeding means, article delivery means, a printer, 110 and means for operating the printer mounted upon said table; with a feed plate and an article track connected with said plate, said track being adapted to support the articles while being operated upon, a spider 115 attached to said plate, and means attached to the table engaging said spider whereby said plate and track may be adjusted relatively to and independently of the printer.

19. In a stamp canceling and postmarking machine, the combination of a table and means for operating upon an article mounted thereon; with a feed plate, a delivery plate, an article track connected with and between said plates and adapted to support 120 the article being operated upon; and supports for said plates adjustably connected with said table whereby said plates and

track may be adjusted relatively to and independently of the operating means.

20. In a stamp canceling and postmarking machine, the combination of a table, article feeding means, delivery means, and means for operating upon articles mounted thereon;—with a feed plate, a delivery plate, an article track connected with and between said plates and supports for said plates adjustably connected with said table top, whereby said plates and track may be adjusted relatively to and independently of the operating means.

21. In a stamp canceling and postmarking machine, the combination of a table, ar-

20
ticle feeding means, article delivery means, a printer, and means for operating the printer mounted upon said table; with a feed plate, a delivery plate, an article track intermediate and connected with said feed and delivery plates, spiders attached to said feed and delivery plates, and means attached to the table engaging said spiders, whereby said plates and track may be adjusted relatively to and independently of the printer and feeding and delivery means.

25
In testimony that I claim the foregoing as my own, I affix my signature.

WALTER H. BOWES.
